DESIGN FOR A FOLDING CHAIR

Walter O. Brown, Detroit, Mich.

Application December 8, 1932. Serial No. 46,327

Term of patent 14 years

To all whom it may concern:

Be it known that I, WALTER O. BROWN, a subject of the King of Great Britain, residing at Detroit, in the county of Wayne and State of Michigan, have invented a new, original, and ornamental Design for a Folding Chair, of which the following is a specification, reference being had to the accompanying drawing forming a part thereof.

The drawing is a perspective view of a chair showing my new design.

The feature of my design resides in the form of the seat member to the under side of which

are secured a pair of U-shaped legs of rod-like form and a U-shaped back member of rod-like form, the forward terminals of each leg member being vertical when in the extended position for use and the rear terminal portion extending to a distance beyond the rear edge of the seat and extending at an angle to the point of connection thereof with the seat.

I claim:

The ornamental design for a folding chair substantially as shown and described.

WALTER O. BROWN.
